SHOE PRESS

Dominik Russo, Boston, Mass., assignor to Russite Corporation, Boston, Mass., a corporation of Massachusetts

Application June 1, 1944, Serial No. 538,245

11 Claims. (Cl. 12—33)

1

The present invention relates to shoe presses and more particularly to the type of shoe press which is used to cement soles to shoes whether in manufacture or in repairing shoes. The invention is particularly useful for cementing all types of soles to shoes, for instance half soles and whole soles for men's and women's shoes whether in manufacture or in repair.

One of the chief difficulties with shoe presses of the prior art is that they can not be used generally for all types of soles with the same effective results. It was quite common in cementing half soles to shoes that sufficient pressure could not be obtained in the instep portion of the sole to make a good bond between the sole and the shoe. Even in the cementing of whole soles, the rear part of the sole quite frequently came loose. In addition to this, the shoe had to remain in the press for some time, not because the cement was not sufficiently quick in drying, but rather because uniform and sufficiently high pressure could not be obtained.

In the present invention both half and whole soles are cemented in comparatively rapid time, in many cases in only about five minutes.

The present invention also provides many other improvements over the prior art, particularly in the construction of the hydraulic press forming a part of the invention and in the relationship of the press and the elements attached to it for forcing the shoe against the pneumatic cushion. The hydraulic press is so constructed that it may be readily removed and replaced by a new one if desired and the elements for supporting the shoe operate in such a fashion that practically no adjustment is necessary when the shoe is put into the press. The pneumatic cushion of the present invention is also particularly constructed in relation to other elements to provide many of the advantages discussed above.

Without further describing the merits and advantages of the present invention, the invention will now be described in connection with an embodiment of the same set forth in the specification below and illustrated in the drawings, in which:

Figure 1 shows a side elevation of the shoe press of the present invention.

Figure 2 shows a front elevation of the shoe press with the pans removed.

Figure 3 shows an enlarged view of a part of the upright portion of the shoe press with fragmentary sections broken away.

Figure 4 shows a section taken on the line 4—4 of Figure 3.

2

Figure 5 shows an enlarged modified sectional detail of Figure 4.

Figure 6 shows a fragmentary top view looking down at the top of Figure 3 with parts in fragmentary section.

Figure 7 shows a side view of the top portion of Figure 3 as viewed from the left.

Figure 8 shows a modified section corresponding to a section taken on the line A—A of Figure 3.

Figure 9 shows a sectional view taken on the line 9—9 of Figure 2.

Figure 10 shows in elevation the detail shown in Figure 5.

Figure 11 shows a plan view of the plan at the bottom of the shoe press.

Figure 12 shows a side view of the element shown in Figure 1 partially in fragmentary section, and

Figure 13 shows a section taken on the line 13—13 of Figure 12.

In the drawings the shoe press has a base 1 and bridge elements 2 and 3 on which the presses 4 and 5 are mounted. In the construction herein shown, the bridges and presses are duplicated or in a twin battery but if desired the construction may be in single units or in more than two.

The bridge is constituted of two side upwardly extending supports 6 and 7 and a central support 8, all formed integrally with the side and central flanges 9, 10 and 11 respectively, all extending upwardly from the base 1, supporting and carrying the cross elements 13 and 14 in which the hydraulic press cylinders 15 and 16 are mounted for vertical operation. As indicated in Figure 3, the cylinder 16 is grooved circumferentially near its lower end at 17 and a set screw 18 threaded through a sleeve or collar 19, formed as part of the cross element 14, holds the cylinder 16 firmly in place.

The whole hydraulic press may be easily removed by simply loosening the set screw 18 and taking the cylinder and the hydraulic press out at the top of the bridge after the last supporting members at the lower part of the press below the bridge have been removed.

This lower mechanism comprises a last support 23 which is carried by a bracket 24 having two inwardly extending flanges 25 and 26 which fit into grooves in the sides of the last support. The bracket 24 is itself forked at its upper end in flanges 27 and 28 to receive the short shaft 29 forming a sleeve for an upright pin 22 which has a flat-headed flange 30. The sleeve 29 with the pin 22 and the bracket 24 are pinned together.

by means of the pin 31 which passes freely through the two forked branches 27 and 28, the sleeve 29 and the upright pin 22. The pin 22 is swivelled in the base of the cap 21 which is threaded at its top end of the piston 20 operating hydraulically with the cylinder 16, as will be explained.

The piston 20 is a tube in which the hydraulic liquid enters so that the cap 21 also provides a seal at the base of the piston 20. This is accomplished by forming a little shoulder within the cap 21, as indicated at 32, and providing suitable cap members or washers 20' or Neoprene or synthetic rubber and 21' of metal which are drawn tight against the end edges of the tube when the cap 21 is threaded on the piston. The pin 22, it will be seen, is free to turn about a vertical axis while the bracket 24 may turn about the horizontal axis of the pin 31. The last support 23 is therefore free to adjust itself along the bracket 24 as the shoe is pressed against the pan since the shoe and last support stay together. The last support 23 is made to slide freely in the bracket 24 and although the contour of the upper surface 32 of the support fits with that of the lower surface of the bracket, the flanges 25 and 26 fit sufficiently close in the grooves in which they slide so that when the support is tipped up, the supporting bracket is turned on the pin 31. The last support 23 is built with a flat rear portion 34 and an arched, downwardly extending front end 35 at the end of which there is a clamping bar 37 supported by a threaded pin 38. The front tip of the last and shoe support is lined with a rubber pad or tip 40 covered by a fabric or leather cover 36. This is held in place between the bar 37 and a flange 39 extending from the front end 35 and provides a frictional hold and guard against the toe of the shoe when in the press. This arrangement of the last support provides a convenient self-adjustment so that the shoe may come down upon the base in the most favorable position without any adjustment or manipulation on the part of the operator.

The hydraulic press 4 comprises the outer cylinder 16 and the inner piston 20 already mentioned together with other elements and members which are shown in detail in Figures 3 to 10 inclusive. The stationary elements in the arrangement herein described is the outer cylinder 16. The piston 20 has positioned within it a second cylinder 41 which is provided with a central fluid or liquid passage 42 through which the hydraulic liquid flows into the tube or piston 20. The cylinder 41 is provided at its end with suitable sealing rings or members shown in modified detail in Figure 5 and Figure 10, the object of the seal being to prevent the hydraulic medium or liquid from escaping between tubes 41 and 20. The cylinder 41 is threaded at the top to receive a threaded collar 43 which provides a communicating passage to the small chamber 44 just above the top of the cylinder 41. The collar 43 is also externally threaded into the inside of the similar cylinder 16 with a tight sealing stationary joint. The tube or piston 20 surrounds the cylinder 41 for its whole length up to a point where 41 enters the collar 43 when the tube 20 is in its uppermost position, as shown in Figure 4. The tube 20 is itself recessed and threaded on its inner side at its top at 45 to receive the cap member 46. The cap 46 is made to provide a sliding fit within the end of the cylinder 41 and has a downwardly projecting threaded collar portion which screws into the internally threaded end at the top of the

cylinder 20. The diameter of the member 46 which is large enough to fill the space within the walls of the cylinder 16 also forms an upper thrust surface for the long spring 47, the purpose of which is to return the piston 20 to its normal inoperative position when the hydraulic pressure has been released.

The lower end of the spring 47 is supported in place by means of a collar 49 which has a sliding fit for the cylinder 20 and is threaded externally into the inner wall of the cylinder 16. As the cylinder 20 is forced downward by the hydraulic liquid entering the chamber 50 within the tube 20, the spring 47 becomes compressed. When, however, the pressure is released and the oil flows out of the chamber 50 through the passage 42 and into the reservoir 51, as will be later described, the spring 47 will expand and raise the piston into its normal and inoperative position. The reservoir 51 at the top of the press communicates with the pump chamber 52 through the passage 53, the check valve 54, the inlet port 55 and the communicating passage 56 which opens into the top of the chamber 52. When the pump handle 57 is in its upright position, the piston 58 is down, as indicated in Figure 9.

As the pump handle 57 is rotated clockwise to the dotted line position 57', the piston 58 is forced up to drive the hydraulic liquid from the chamber 52 into the passage 60 against the valve 61 which is provided with a fluted stem 61' guiding the valve in the passage 60 while permitting the liquid to flow past the valve without resistance. The liquid then passes through the port 62 into the chamber 44 from whence it flows down through the passage 42 into the chamber 50. The pump handle 57 carries a cam 63 and the latter is pivoted in a forked bearing 64 by means of the pin 65 which passes through both the forked bearing and the cam and provides an eccentric motion for the cam such that the roller 66 is given an upward component without any side thrusts. Bringing the handle 57 downward in its clockwise rotation therefore pumps the oil through the passage 42 and forces the piston 20 downward thus enlarging the liquid chamber 50. When the pump handle is released or returned to its upright position, the spring 67 returns the piston 58 to its normal position, that is, it forces it downward, as viewed in Figure 4. This permits the chamber 52 to be filled again so that when the handle 57 is again rotated clockwise downward more liquid will be forced into the chamber 50 and the piston 20 will continue to travel downward, as viewed in Figure 4.

While in the operation described, the handle 57 is rotated downward to pump the liquid into the chamber 50, the cam may be so arranged that the pump handle could be worked in the other direction, that is raised in pumping the liquid into the chamber 50. The liquid sealing member at the lower end of the cylinder 41 comprises a cup-shaped synthetic rubber or rubber washer 70 compressed and held in a recess at the bottom of the shaft 41 by means of a cap 71 which is held in place by the two nuts 72 and 73 threading over a reduced shoulder at the end of the cylinder 41.

A more preferred form of construction is illustrated in Figures 5 and 10. Here the cylinder 41 is provided with an external sleeve 78 made to have a smooth sliding fit. The cylinder 41 is also threaded internally at its end to receive the threaded cylindrical end member 74 which is provided with a long neck 75 at its end, furnishing a communicating passage 76 through which the hy-

draulic liquid will flow into the chamber 50. The bushing or sleeve 78 rests in a shoulder on the cylinder 41 and forms, with the end of the cylinder 41 and a recess at the side of the member 74, a cup-shaped recess for the purpose of receiving a correspondingly outwardly curved shaped cup washer 71, preferably of leather, which fits around the long neck of the member 75. A rubber or synthetic rubber washer 79, such as Neoprene, has one end firmly resting within the cup 71 with the lower end of the washer flaring outward in a conical fashion against the wall of the tube 20. This washer is capped with a metal disc washer 80 forced upward by the spring 81 against which the nuts 82 and 83 are tightened. The rubber or synthetic rubber washer 79 is bevelled outward so that it forms a pressure contact against the inner wall of the tube 20 and the nuts and spring furnish resilient pressure against the wall of the tube to permit the piston to operate easily while the seal of liquid is maintained. The ring element at the end of the tube 58 is the same as that at the end of the tube 41 but a construction similar to that shown in Figures 5 and 10 may be used.

After the shoe has been cemented and when it is desired to release the piston, this is accomplished by operating the small hand lever 90 (see Figure 3). The small hand lever 90 controls the action of the pin 91 which has a flat flange 92 at its inner end positioned opposite the fluted stem 93 of the valve 94. When the pin 91 is moved longitudinally in the bushing 95 by rotating the handle 90 from the full line to the dotted line position 90' then the valve 94 is moved to the right and the reservoir 51 is connected through the communicating passage 96 and then through the passage 97 along the fluted stem 93 through the valve 94 into the chamber 98 through the inlet 99 (see Figure 6) to the small chamber 44 at the top of the cylinder 41 (see Figures 6 and 4). It will be noted then that the pressure in the chamber 50 will be relieved and the hydraulic liquid, which may be oil, water or other suitable medium, will flow back into the chamber 51. The liquid in the chamber 50 will also be relieved and flow back to the reservoir if the valve is released or releases itself because of excess pressure in the chamber 50. The valve 101 (Figure 4) may be set at a desired pressure to release if too much pressure is exerted by the press. This pressure may be set at the desired value simply by removing the top cover plate 102 on the reservoir and adjusting the spring tension by means of the threaded plug 103 on the end of the valve stem.

The release valve operated by means of the lever 90 operates to release the pressure within the chamber 50 by rotating the handle downward to the dotted line position shown in Figure 3. By proper construction of the eccentric cam portion 110, the handle may be operated in the reverse direction thus making use of the weight of the handle to maintain the release valve either in its closed or open position.

A modification of the construction shown in Figure 3 is illustrated in Figure 8. In this case the chamber 98 and the valve 94 are the same as that shown in Figure 3 and so also the fluted stem 93 which guides the valve 94 in the passage 111. In the wall 112, however, there is provided a recess in which a diaphragm 113 may be positioned. This diaphragm may be made of flexible, yielding material as, for instance, rubber, synthetic rubber, fabric, Bakelite or other plastic materials clamped about its edges in the wall. The diaphragm is provided with a button 114 at

the center having metal surfaces, the inner one of which operates against the fluted stem 93 of the valve 94. Resting against the button surface on the outside of the diaphragm 113 is a sliding pin 115 which projects through the base of the forked bracket 116 which supports the operating lever 90 not shown in Figure 8. This construction may be preferable to that shown in Figure 3 since the operating pin or piston 115 does not have any oil pressure or liquid working against it and therefore need not be sealed by washers as is the case in the construction shown in Figure 3 where the bushing 95 in the block 117 is employed for making a seal with a pair of washers forced against the operating pin or shaft 91.

The mechanism just described for providing pressure operates in connection with a so-called pan 120 which is adjustably positioned on the base 1 between the bridge supports. This pan 120 is shown more in detail in Figures 11, 12 and 13 and comprises a cast base 121 dished with upwardly extending sides 122, 122 which merge into a supporting plate or web 123 which has a downwardly projecting skirt 124 extending all of the way around the pan. The plate or web, which is normally horizontal, is recessed to receive a clamping ring 125 positioned at its face which is held to the web by a group of screws 126. This clamping plate holds down the cover 127 of the pneumatic cushion 128. The form of the pan and the shape of the cushion is particularly important in producing the proper and rapid cementing of the soles to shoes.

It will be noted that the pan is quite deeply dished with a rear supporting flange 129 which is somewhat lower in the center section than the side wall of the pan. The pneumatic cushion 128 projects considerably above the rear wall 129 in the section 130, this section continuing upward in approximately the same direction as the wall 129 and also quite abruptly ending at a level of the top surface 131 of the cushion. The cushion is considerably higher than the pan itself, approximately twice as high, and furnishes a large yielding area so that the shoe and sole may be uniformly held under pressure over the whole cementing surface merely by forcing the sole of the shoe against the cushion with the hydraulic press.

The cushion itself comprises an internal bladder 133 which is shaped to fit within the dished pan and extends upward beyond it to about the same height. This bladder is not intended to expand greatly and therefore is made of heavy rubber and shaped with a short rear corner 134 but otherwise elongated to fill out the whole pan. Air is supplied to the cushion at the front end through a valve 135. A gauge 136 is also provided so that the pressure on the cushion may be known. The pressure in the cushion may be properly adjusted by the amount of air pumped into the cushion. Prior to the pressing of the shoe against the cushion, the pressure may be 20 to 30 pounds and subsequent thereto, when the shoe is in place for cementing, the pressure may be raised to 40 or 50 pounds, depending upon the range and operation which is desired and for which the machine is designed.

The bladder is covered with a durable cover which comprises an internal fabric 137 such as canvas, leather or other durable materials faced on both sides by a rubber or synthetic rubber facing 132. The cover is provided with a flanged edge 138 which is received beneath the clamping ring 125 and also with an end apron 139 which

covers over the back of the bladder and is tucked in between the wall 129 and the corner of the base 140 against which the bladder lies. This furnishes a retaining wall for the back of the bladder and permits the cushion to be built up high in the rear of the pan to a height about twice the height of the pan. This construction is particularly important to permit proper pressure to be exerted at the instep portion of the sole so that even pressure may be maintained between the shoe and the sole as it is cemented. The building up of the rear part of the cushion above the top of the rear wall permits a considerable downward movement of the shoe and this allows a self adjustment of the shoe and the sole to provide uniform and even pressure over the cementing area. The flanged edge 138 is provided at its periphery with a bead 141 which rests in a groove extending around the face of the plate 123.

In the operation of the device, the operator inserts the last in the shoe and places it against the last support 23. The sole surface may be previously prepared with proper cement. The hydraulic piston is then lowered, forcing the sole of the shoe against and into the cushion until the desired pressure is indicated on the gauge 136. The last will adjust itself in position to provide a uniform pressure over the entire sole, preserving particularly the pressure on the instep and toward the heel. The shoe is left in the press for the desired length of time. With the present machine soles have been cemented in approximately five minutes because of the pressure which can be applied between the sole and the shoe. This will permit the use of a quick drying cement and also will permit a greatly increased production and use for the machine.

Having now described my invention, I claim:

1. A shoe press of the type described comprising a base member having a span support, a pan having a pneumatic cushion positioned in said base, a hydraulic press having a cylinder fixed in said span support, a piston operating in the cylinder, a coupling member having one portion attached to the piston end and having a second portion coupled to the first portion in a vertical swivel joint, a block horizontally pivoted to said second portion, said block having a guideway and a last support slidably therein, said piston being positioned over said pan and acting in a direction substantially perpendicular to the surface of the pan.

2. In combination in a shoe press, a base member having a span support, a pan having a pneumatic cushion positioned in said base and a hydraulic press having a cylinder fixed in said span positioned normal to the surface of the pan, said press having a hollow, movable cylinder operating within said fixed cylinder, a second fixed cylinder positioned within the moving cylinder axially aligned therewith and serving as a bearing surface for the movable cylinder and having a hydraulic seal against the inner wall of said moving cylinder, a communicating passage within said second cylinder opening to the chamber formed by the hollow wall of the moving cylinder, a long compression spring acting between the first fixed cylinder and the moving cylinder to return the moving cylinder when hydraulic pressure has been released, a last support for pressing the shoe sole against the pneumatic cushion of the pan, and a coupling member attaching said last support to the end of the moving cylinder, said coupling member permitting

rotational motion about both vertical and horizontal axes, and a lateral adjustment of the last support whereby the last support may settle the shoe in the cushion with only axial motion of the movable cylinder.

3. In a shoe press of the type described, a base member having a span support, a hydraulic press having a fixed cylinder mounted in said span, a hollow, movable cylinder operating axially within said fixed cylinder, a shoe last support comprising a bridging member having ends adapted to bear on the last and having elongated grooves in the sides of the bridging member in the front portion thereof, a bracket support fitting over the top and sides of said bridging member and having inwardly extending flanges fitting in said grooves, said bracket having a recessed top, means firmly attached to the end of the moving cylinder providing a swivel joint having its axis concentric with that of the movable cylinder, a pin extending at right angles to the axis through said joint, said pin being journaled in the recessed top of said bracket into which the swivel extends.

4. In a shoe press of the type described, a base member having a span support, a hydraulic press having a cylinder and hollow piston therein, means mounting said cylinder perpendicularly in said press, a pan removably mounted adjustable in said base with the surface thereof normal to action of said piston, a shoe last support, means coupling said last support to said movable piston swivelling said last support in a perpendicular axis including a cap member sealing the end of said hollow piston and having a perforation through which said swivelling means extends, said perforation having a shoulder, and a swivelling means having a corresponding flange resting thereon.

5. In a shoe press of the type described, a hydraulic press having a fixed cylinder, a movable cylinder within the fixed cylinder having a hollow center chamber, means for capping the open end of the hollow cylinder including a cap element having an internal recessed shoulder, a sealing washer supported on the shoulder adapted to be held by the cap against the open end of the cylinder, and a swivelling pin having a head, said head resting in the recess within said cap and said pin extending through an opening in the base of the cap.

6. In a shoe press of the type described, a base member having a pan supporting a pneumatic cushion, said cushion comprising a bladder resting against the base of the pan and extending substantially above the level of the pan, a cover covering said bladder having a peripheral flange and means for clamping said flange to the top face of the pan around the front and the sides, said cover having an apron at the back thereof folding over the end of the bladder and extending into the pan between the bladder and the base of the pan.

7. In a shoe press of the type described, a pan having a pneumatic cushion contained therein, said pan being dished and having a flat clamping surface around the front and the side thereof, a bladder positioned in said pan filling out the dished area and extending substantially above the clamping surface of the pan, said bladder being substantially flat on top, a cover fitting over the top of the bladder and having an extending peripheral flange lying over the clamping flange on the sides and front of the pan with an apron extending over the back of the bladder and inserted between the wall of the pan and

the bladder at the back thereof, the back of said cushion being substantially as high as the rest of the cushion and a clamping ring extending around the side and front of the pan for clamping the cover to the flange of the pan.

8. In a shoe press of the type described, a base member having a pan fitting therein containing a pneumatic cushion, said pneumatic cushion comprising a bladder filling the said pan, said pan having a flat outwardly extending flange about the side and front thereof with the edge of the pan recessed at the back thereof, a cover fitting over said bladder with a flange extending over the flange of said pan and a portion extending over the back of the bladder into the pan between the rear wall and the bladder, a clamping ring clamping the flange of said cover to the flange of the pan, the back of said pan being recessed and said pneumatic cushion extending at the back of said pan substantially above the recessed rear wall thereof.

9. A shoe press of the type described, comprising a base, a pneumatic cushion in said base, a support secured to said base and carrying a fluid pressure-operated piston vertically movable in alignment with said base, means to adjust said fluid pressure and to release said pressure, a last support associated with said piston having means for movable adjustment to provide a self-seating of the shoe and last on the pneumatic cushion, said means comprising a coupling member providing longitudinal adjustment of said last support, a vertical swivelling member, said coupling member being horizontally journalled in said vertical swivelling member, and means supporting said vertical swivelling member in alignment with said piston.

10. A shoe press of the type described, having a pneumatic cushion supplied with a predetermined pressure to contact with a shoe sole on a last, a pressure indicator for said cushion, fluid

pressure-operating means movable in vertical alignment with the last and having a flexible bearing on said last, manual operating means to build up said fluid pressure thru the last against the cushion, in combination with adjustable means to release the fluid pressure on the last when a predetermined amount of pressure has been built up in the pneumatic cushion.

11. A shoe press of the type described comprising a base member having a span support, a pan having a pneumatic cushion positioned in said base, a hydraulic press mounted and supported in said span support with a movable piston member operative in a direction normal to the surface of the pan, a hydraulic pump element formed as a part of said hydraulic press and rigidly connected thereto, a handle for operating said pump and thereby moving said piston in the direction of said pan, said handle being positioned adjacent said movable piston, a last support and means mounting the last support on the end of the piston, said means permitting lateral and pivotal adjustment of the last support in both horizontal and vertical axes.
